UNITED STATES PATENT OFFICE.

HUGH DE HAVEN, JR., OF SAN FRANCISCO, CALIFORNIA, ASSIGNOR TO TI-IT MACHINE COMPANY, OF SAN FRANCISCO, CALIFORNIA, A CORPORATION OF CALIFORNIA.

PROCESS OF AND APPARATUS FOR FORMING WIRE TIES.

Application filed June 15, 1921. Serial No. 477,645.

To all whom it may concern:

Be it known that I, HUGH DE HAVEN, Jr., a citizen of the United States, and a resident of the city and county of San Francisco, State of California, have invented a certain new and useful Process of and Apparatus for Forming Wire Ties, of which the following is a specification.

The invention relates to the art of securing together wires or the ends of a strand of wire which is placed around a package for protecting the package during shipment and relates particularly to the art of twisting together the ends of a strand of wire which has been drawn taut around a box, or twisting together two wires.

In the art of securing wires around boxes, the procedure has been to pass a wire around the box, draw the wire tight and then twist the ends of the wire together to form a tie or lock. The desired end to-be accomplished is to form a tie or lock which will withstand as great if not a greater strain than the wire and it has usually been considered desirable to form a tie which will hold under a tension sufficiently great to rupture the wire. Attempts to reach this desired end have not culminated in uniformly successful results. The two ends of the wire strand have been twisted together a plurality of times, but it has been found that when the ends were twisted together that the wire was weakened at the twist during the twisting operation, so that when tension was later placed on the wire, it broke at the twist. Devices for twisting together the ends of a wire strand surrounding a package are usually manually operated and the twist that they are designed to produce should be of such form that the device can be easily operated by one man. The twist which can be formed most satisfactorily by a hand-operated device, is a double twist, that is, a twist formed by the rotation of a twisting element through two complete revolutions. Great difficulty has been experienced in the past in producing a satisfactory double twist, since if the twist is formed loosely it will unravel under tension and if formed too tightly, the wire is so weakened during the twisting operation, that the twist will rupture under tension. To overcome this difficulty, it has been proposed to form the tie of three twists, pro-

duced by the rotation of the twisting element through three complete revolutions. This, however, in a hand machine requires the use of a long, unwieldy operating lever or of a crank, either of which is objectionable.

In accordance with my invention, I have provided a double twist tie, or as it is termed in the art, a two-twist tie, which has a holding power not less than the tensile strength of the wire and which is so formed that the wire is not mutilated in the twisting operation. It is to be understood, however, that my invention is not limited to a two-twist tie, since it may be embodied in a tie having a greater number of twists. I have formed two-twist ties using No. 13 gauge baling wire and have found that the ties so formed are of uniformly greater tensile strength than the wire. I have found that it is not necessarily the number of twists which determines the effectiveness of the tie, but rather the form of the twist and after a careful analysis of the problem I have produced the very efficient twist of the present application.

An object of my invention, therefore, is to produce a wire tie, preferably of the two-twist type, wherein the twists are so formed that the tie has a tensile strength equal to or greater than the wire and in which the wire is not weakened so that under tension it will not break or unravel at the twist.

A further object of the invention is to provide a process of twisting the ends of a wire, or wires, together so that the above desirable results will be obtained.

A further object of the invention is to provide an apparatus for forming the desired twist.

The invention possesses other advantageous features, some of which, with the foregoing, will be set forth at length in the following description, where I shall outline in full the twist of my invention, the method of forming the twist and one form of apparatus for forming it. In the accompanying drawings I have shown one form of twist of my invention and the apparatus for forming it, but it is to be understood that I do not limit myself to such form of twist or apparatus, since the invention, as set forth in the claims, may be embodied in a plurality of forms.

Referring to said drawings:

Figure 1 is an elevation, somewhat diagrammatic, of the twisting gear heretofore generally employed, showing a twisted tie 5 therein.

Fig. 2 is an elevation of one form of twisting gear of my invention.

Fig. 3 is an elevation of another form of twisting gear of my invention.

Fig. 4 is a side elevation of the twisting gear shown in Fig. 3, with a portion of its cooperating driving gear.

Fig. 5 is a side elevation of a twisted tie formed in the gear shown in Fig. 3.

Fig. 6 is a plan of the twisted tie shown in Fig. 5.

In tying a wire on a package, the usual procedure comprises passing the wire around the package and disposing the overlapping ends of the wire in close relation in a rotatable twisting element and in guides or holding members flanking the twisting element. The guides usually comprise blocks having alined slots therein, of a height sufficient to receive the wire, but not sufficient to permit the wires to move bodily during the twisting operation. The guides, therefore, serve the function of preventing the wires from twisting over each other, so that 20 the twist is confined between the guides. Disposed between the guides is the rotatable twisting element which is provided with a slot in which the overlapping wires are disposed. The slot is usually narrower at the 25 center, its height at that point being substantially the same as the slots in the guides and for the same purpose. At both ends, the slot in the rotatable twisting member is increased in height to provide space wherein 30 the twist may form. Prior to the twisting operation, the wire is drawn taut around the package, so that the wire ends lie in substantially parallel relationship in the grooves in the guides and twisting member. One 35 form of assembled mechanism for forming twisted wire ties is shown in the co-pending application of myself and C. L. Drew, Serial No. 414,108, filed October 1, 1920, to which reference is hereby made for a disclosure of a complete wire tying device. The present invention, however, is not in any manner limited to the showing made in such application, since the tie of the present invention may be formed in devices of different structure, and since the tie may be used for other purposes, such as for securing 40 together two wires.

The twisting element usually comprises a gear 2 having integral stub shafts 3, suitably 45 journaled in pillow blocks 4, and engaged by a driving gear 5. The gear unit, consisting of the gear and the stub shafts, is provided with a longitudinal slot 6 extending radially from the periphery, to and slightly 50 beyond the rotational axis. The depth of

the slot is preferably such that when two wires are disposed longitudinally in the slot in close relation, as shown in Fig. 4, the wires lie close to or on opposite sides of the axis of rotation. At its central portion 7, 70 the slot is of just sufficient height to readily receive a wire, so that as the gear is rotated the wires at the narrow portion are incapable of relative bodily movement. At the opposite ends, the slot is increased in height, to 75 form two chambers 8 and 9 in which the twist is formed. The widening of the slot produces shoulders 12 and 13 at opposite ends of the gear unit, which serve as anvils against which the wire is bent as the gear unit rotates. It has been the practice heretofore, to position these shoulders 12 and 13 directly opposite each other, as shown in Fig. 1, with the result that as the gear is rotated both wires of the twist start to bend at the 80 same point longitudinally of the twist. One wire bends upwardly, crossing over the other wire, and being forced thereby against the upper shoulder 12 with great pressure, and the other wire bends downwardly, crossing 85 under the other wire and being forced thereby against the lower shoulder 13 with great pressure, the pressures being the bending pressure of the wire and the additional pressure caused by the opposing pressure of the 90 other wire. The wires are not only subjected to pressure and torsion, but since they move laterally in twisting, the shoulders produce a shearing strain. These effects cause the shoulders to bite sharply into the two wires, 95 weakening the wires and consequently weakening the ultimate twist. By virtue of this construction, also, the convolutions of both wires, forming the twist, are uniformly axially displaced with relation to the longitudinal axis through the gear unit, and experience has proven that upon subjecting such 100 twist to tension, it will often pull apart or unravel, without breaking the wire. Such twist as that shown in Fig. 1 does not possess 105 a tensile strength equal to or greater than the wire and when subjected to tension will either rupture at the point of beginning of the twist, where the shoulders have mutilated the wire, or will pull apart, and either 110 of these conditions will usually occur before sufficient strain has been placed on the wire to rupture it at an untwisted portion. If the twist is formed tightly, the biting action of the shoulders will materially weaken the 115 wires and if it is formed loosely it will unravel under tension.

In accordance with my invention, I form the twist in such manner that the beginning of the twist in one wire is spaced longitudinally from the beginning of the twist in the other wire so that the injurious biting action of the shoulders against the wire is obviated, and so dispose the convolutions of the twist, 125 that when strained the full convolutions of 130

each wire pull directly against each other. In the construction of gear unit shown in Fig. 2, the upper shoulders 12 are spaced apart a greater distance than the lower shoulders 13, so that one wire starts to bend at the shoulder 13 whereas the other wire starts to bend at the shoulder 12, so that the injurious effect of the shoulders on the wire is minimized.

10 Substantially the same result is obtained with the form of gear unit shown in Fig. 3, wherein only one shoulder 12 and one shoulder 13 is employed, the faces of the slot opposite the shoulders being preferably smooth and unbroken. The shoulders are preferably slightly beveled, as shown at 15, to further lessen the biting effect on the wire. By this arrangement of the shoulders, one twist forming chamber 8 is disposed partly above 20 the axis of the gear unit and the other twist forming chamber 9 is disposed partly below the axis, so that the twists are displaced oppositely with relation to the axis of the gear unit and with relation to the untwisted central portion of the tie. Instead of both wires being pressed against shoulders at both sides of the untwisted central portion, only one wire is pressed against a shoulder and the other wire bears or wears against a smooth 30 surface. I have found that the tie formed by the gear unit shown in Fig. 3 is somewhat preferable to the tie formed by the gear unit shown in Fig. 2, although the tie formed by the gear unit shown in Fig. 2 is preferable 35 to the tie formed by the gear unit shown in Fig. 1.

In Figs. 5 and 6, I have shown the twist as formed by the gear unit shown in Fig. 3. The two ends 16 and 16^a of the wire are 40 disposed in overlapping relation and twisted, as heretofore set forth, forming a central untwisted portion flanked by the twisted portions 17 and 18. In forming the particular twist shown, the gear unit is rotated 45 through two complete revolutions, forming a double twist on each side of the central untwisted portion. In the drawings, I have shaded the two wires 16 and 16^a differently so that they may be readily identified in 50 the twist. In order to produce a tie having the desired qualities, I find it advisable to form the twist in such manner that the initial points of bending of the two wires be spaced apart longitudinally. Referring to 55 the twist 17, it will be seen that the wire 16 departs from the straight or untwisted portion at the point B and that the wire 16^a departs from the untwisted portion at the point C and that the points B and C are 60 spaced longitudinally of the tie. The wire 16 bends over the shoulder in the twisting element while wire 16^a wearing against a smooth supporting surface forces wire 16 over it, axially displacing the twist from the 65 axis of the rotating center section. It will

be seen that wire 16^a cannot crowd into the initial twisting point B of wire 16 and, therefore, is compelled to begin its twist from another point C. The same conditions obtain in the twist 18 wherein the wire 16^a starts bending at D and the wire 16 starts bending at E. In the twist 18 (see Fig. 5) the wires in the convolutions are completely disposed below the plane of the upper surface of the central untwisted wire and in 75 the twist 17 the wires in the convolutions are completely disposed above the lower surface of the wire in the untwisted central portion. This produces in the wire 16 in the twist 17, one normal hump or convolution 22 and one 80 abnormal hump or convolution 21, between which is disposed the hump 23 in the wire 16^a and in the twist 18, produces a normal hump 26 and an abnormal hump 25 in the wire 16^a between which is disposed the hump 85 27 in the wire 16. When tension is placed on the wire surrounding the package, the strain is placed principally on the wire 16 in the twist 17 and the wire 16^a in the twist 18 tending to straighten these wires, and a 90 lesser straightening strain is placed on the wire 16^a in twist 17 and on the wire 16 in twist 18. The humps 23 and 27, therefore, are maintained in form and form abutments 95 against which the abnormal humps 21 and 25 are pulled. This produces a tie which has a greater tensile strength than the untwisted wire, due both to the shape of the twist and the fact that the wires are not weakened by being cut into by shoulders on 100 the twisting element. While I have shown two forms of twisting elements which may be employed to produce the tie of my invention, it is to be understood that other devices 105 may be used for producing the tie and that the tie is not limited in its formation to any particular form of apparatus, nor to any form of use or application, nor to any specific number of twists, although for hand formed ties, the double or two revolution 110 twist is preferable.

I claim:

1. The method of securing wires together, which comprises disposing said wires in overlapping relation, holding said wires in overlapping relation, holding said wires at spaced points, rotating the two wires bodily intermediate said held portions whereby two twists are produced and forming said twists so that one twist is disposed wholly below the upper surface of the wire 115 at the intermediate untwisted portion and the other twist is disposed wholly above the lower surface of the wire at the intermediate untwisted portion.

2. The method of securing wires together, 125 which comprises disposing said wires in overlapping relation, holding said wires in overlapping relation, holding said wires at spaced points, rotating the two wires bodily intermediate said held portions whereby two twists are produced separated 130

by an intermediate untwisted portion and controlling the wires at the junctures of the twists with the untwisted portion so that the points of initial bending of the wires at the juncture of a twist and the untwisted portion are spaced apart longitudinally.

3. The method of securing wires together, which comprises disposing said wires in overlapping relation, holding said overlapping wires at spaced points, rotating the two wires bodily intermediate said held portions whereby the wires are twisted together between the intermediate portion and the held portions, and causing one wire in each

twist to bend over a shoulder and the other 15 wire to bend over said first wire.

4. In a wire tying machine, a rotary wire twisting member, having a longitudinal slot therein adapted to receive the wires to be twisted, one face of said slot being depressed 20 adjacent one end of the member and the other face of the slot being depressed adjacent the other end of the member, the surfaces of the slot being otherwise unbroken.

In testimony whereof, I have hereunto set 25 my hand.

HUGH DE HAVEN, JR.
